Primary Examiner — Cary M Robinson*Assistant Examiner* — Adam C Mager(74) *Attorney, Agent, or Firm* — Daryl R. Wright; Greg Carr(57) **CLAIM**

We claim the ornamental design for a model vehicle axle carrier, as shown and described.

DESCRIPTION

FIG. 1 is an upper, right, front perspective view, including the mirror image, of a model vehicle axle carrier showing our new design;

FIG. 2 is a left side view thereof;

FIG. 3 is a right side view thereof;

FIG. 4 is a front elevation view thereof;

FIG. 5 is a rear elevation view thereof;

FIG. 6 is an upper plan view thereof;

FIG. 7 is a lower plan view thereof; and,

FIG. 8 is a lower, right, rear perspective view of the model vehicle axle carrier.

In the drawings, the broken lines illustrate portions of the model vehicle axle carrier that form no part of the claimed design.
